UNITED STATES PATENT OFFICE.

FREDERIC J. PARK, OF WHEELING, WEST VIRGINIA.

DESIGN FOR A BOTTLE.

SPECIFICATION forming part of Design No. 17,215, dated March 29, 1887.

Application filed February 14, 1887. Serial No. 227,617. Term of patent 7 years.

To all whom it may concern:

Be it known that I, FREDERIC J. PARK, of Wheeling, in the county of Ohio and State of West Virginia, have invented a new and useful Design for Decanters; and I do hereby declare the following to be a full, clear, and exact description thereof.

The design is illustrated in the accompanying drawings, in which Figure 1 is a side view of a bottle embodying the design. Fig. 2 is an end view thereof, and Fig. 3 is a horizontal cross-section on the line $x-x$ of Fig. 2.

Like symbols of reference indicate like parts in each.

15 The body of the bottle is oblong in cross-section. The bottle flares upward and outward from the base a to the line $b-b$, and from thence the sides of the bottle are gradually contracted or tapered upwardly to the line $c-c$, where it is further contracted to form the bottle-neck f . The sides d of the bottle are somewhat convex, as shown in the drawings. The narrower sides

e are provided with a raised figure. The sides d have not this figure.

The leading features of the design are indicated in the following claims:

1. The design for bottles, consisting in a bottle oblong in cross-section, having a base, a , and sides extending upward to the line $b-b$, and thence tapering upward to the base of the neck, 30 substantially as shown and described.
2. The design for bottles, consisting in a bottle oblong in cross-section, having a base, a , and sides extending upward to the line $b-b$, and thence tapering upward to the base of the neck, 35 the opposite narrow sides being provided with a raised pattern, substantially as shown and described.

In testimony whereof I have hereunto set my hand this 10th day of February, A. D. 1887.

FREDERIC J. PARK.
